UNITED STATES PATENT OFFICE.

ISIDOR KITSEE, OF PHILADELPHIA, PENNSYLVANIA.

TELEPHONE SYSTEM.

No. 846,413.

Specification of Letters Patent.

Patented March 5, 1907.

Application filed April 8, 1904. Serial No. 202,209.

To all whom it may concern:

Be it known that I, ISIDOR KITSEE, of the city and county of Philadelphia, State of Pennsylvania, have invented certain new and useful Improvements in Telephone Systems, of which the following is a specification.

My invention relates to an improvement in telephone systems, and has more special reference to such systems wherein two or more outlying subscribers' stations center in one exchange and wherein in such exchange, with the aid of switching arrangements, one outlying subscriber may be connected to a second outlying subscriber. The switching in such exchanges is accomplished with the aid of plugs inserted in jacks placed in apertures of switchboards, and it is well understood that, the size of each switchboard being limited, only a limited number of subscribers can be accommodated therein, five to six thousand being the usual limit, and that partially on account of the greater number of subscribers secondary exchanges have to be employed.

It is one of the aims of my invention to so arrange the terminals of the incoming subscriber-circuits that a greater number of such circuits can be accommodated on a board of the size as now employed; and it is also one of the objects of my invention to simplify the construction of the board as well as plug and jack and also the operations necessary for the connecting of two subscribers.

To this end my invention consists of the devices and arrangements, as will hereinafter be described, illustrated in the drawing, and more clearly pointed out in the claims following this specification.

Referring to the drawing, Figure 1 is a diagrammatic view illustrating two outlying stations and their normal connections at the exchange. Fig. 2 is a perspective view of a switch as used in the exchange for the cutting in or out of the operator's telephone. Fig. 3 is a perspective view of one of the plugs used with my invention. Fig. 4 is a sectional view of a switchboard, showing one of the plugs in position. Fig. 5 is a corner portion of same in plan. Fig. 6 is a bell used at the outlying station, partially in elevation and partially in diagram, showing the connection of the circuits thereto.

Similar numerals indicate similar parts, with the exception that in Fig. 1 the numerals designating parts of one circuit are

also provided with the letter *a*, so as to clearly define the two circuits which are illustrated in this figure.

In the Fig. 1, 1 and 2 are the line-wires connecting the outlying stations to the exchange. In this outlying station I have omitted all details of the apparatus, as the same do not form part of my invention, and I have only shown the lever 3 resting on one terminal of the bell 5, the other terminal of which is grounded at 6. I have also shown in conventional sign the transmitting device, (designated by 4.) The receiver is placed on the hook, but not connected, as the connection of this receiver can be made in any of the approved manners of to-day without interfering with my invention. The line 1 is connected in the exchange to the positive pole of the common battery 9, and the line 2 is connected in the exchange, first, to the coil 7 of a repeater, thence to wire 8 and the negative pole of the battery 9. This repeater is provided with the second coil 10, the soft-iron core 11, and the two armatures 12 and 13. The armature 12 rests normally—that is, when the circuit is not in use—against a branch of the wire 8, thereby making electrical connection with said wire. The armature 12 connects electrically with one terminal of the coil 10, the other terminal of which is connected through wire 24 with the coil of the electromagnet 25, and the other terminal of this coil is connected to wire 26, carried along the switchboard, and is provided with the branch 27, terminating each in one of the jacks at one of the switchboards. These jacks consist simply of the tubular conductors 48. (Illustrated more fully in Fig. 4.) At this junction of the terminal of the coil 10 where the same connects with wire 24 there is also connected electrically thereto the wire 15. To this wire is electrically connected the lamp 16, connected with its other terminal to wire 14, having inserted in its circuit the electromagnet 17. The wire 14 terminates with the armature 13. Between the wire 15 and the lamp 16 are the contacts 44 and 45 of the switch 37, as illustrated in detail in Fig. 2, the contact 44 in electrical connection with wire 15 and the contact 45 in electrical connection with wire 38 and through same with the lamp 16. In Fig. 2 this switch is illustrated as to consist of the pivoted lever 41, provided with the conducting-plates 42 and 43. These conducting-

plates are in electrical contact with wires 35 and 36, designed to be the terminals of the operator's telephone.

Normally—that is, when the operator's telephone should not be inserted in the circuit—the switch is in a position as illustrated in Fig. 2 and the two contacts 44 and 45 are in electrical connection with each other; but when the operator's telephone should be inserted in the circuit the switch-handle is moved between the two contacts, thereby separating the same and inserting between them the conducting-plates 42 and 43, and as the same are connected to the terminals of the operator's telephone it is evident that the same is now inserted in series with the line, allowing the operator to communicate with the subscriber connected to this circuit. The core 11 of the repeater is provided on each side with one contact-point, the contact-point in proximity to armature 12 being connected through wire 23 to the negative pole of the battery 22, and the contact-point in proximity to armature 13 is connected through wire 21 to the positive pole of said battery 22. On the desk 40, at which the lamp 16 is placed, is also placed for each of the circuits in charge of the operator a lamp (designated at 29) connected with one terminal to one pole of the battery 31, the other pole of which is connected to wire 32, terminating at the point secured to the electromagnet 17. The armature 18 of this electromagnet is grounded at 19. The second terminal of the lamp 29 is connected to the cord 33 of the plug 34. This plug consists simply of a round conductor divided at the part designed to come in contact with the conducting-tube 48 into two parts, (designated as 46 and 47,) this for the purpose of securing the plug firmly in said tube. The wire 32 is, through wire 28, in electrical contact with wire 26. For better identification I call one of the subscribers' circuits as an entirety "circuit A" and the second of the subscribers' circuits "circuit B."

Normally—that is, when none of the circuits are in use—the devices are in a position as illustrated in the drawing. Should now subscriber B call up the exchange by removing the receiver from the hook 3 the current from the battery 9 will, as usual, flow through lines 1 and 2; but it will at the same time flow through coil 7, thereby energizing the core 11 and drawing both armatures 12 and 13 toward it and in contact with wires 23 and 21. Through this manipulation the circuit of the battery 22, which embraces the annunciating-lamp 16, will be closed, and through the lighting of this lamp the operator will be notified that this circuit is calling. She will then close switch 37, thereby inserting her telephone in the circuit calling and conversing with the subscriber pertaining thereto. It is

supposed that this subscriber wishes to communicate with subscriber A. The operator simply places the plug 34 into the jack 48^a of her own switchboard. This operation will have the following results:

First. As the electromagnet 17 becomes energized through the closing of the circuit of the lamp 16 the armature 18 will be drawn in contact with wire 32, and as now the battery 31, including in its circuit the lamp 29, is connected through plug 34, tube 48^a to branch wire 27^a of the wire 26^a, and as this wire is, with the interposition of electromagnet 25^a, coil 10^a, armature 12^a, wire 20^a, coil 7^a, line 2^a, lever 3^a, bell 5^a, connected to the ground at the subscriber station A, it is obvious that the circuit of the battery 31 is established through the grounds 19 and 6^a and that therefore the bell 5^a will ring, notifying the subscriber that his circuit is called. I will say in passing that I do not make use of the bell as usually employed, answering only to high-tension alternating current as generated by magnetos, but I make use of a bell and arrangement of same well known, answering to a voltaic current and being kept in motion by the alternate shunting of its electromagnet—an arrangement well understood, and therefore not necessary to be described here in detail. The reason why I discard the bell depending on the high-tension magneto is that, more especially where paper-covered wires are employed, this paper is easily pierced by such impulses, thereby becoming defective, and I employ the arrangement as illustrated in Fig. 6, wherein the electromagnet is alternately shunted through the striking of the clapper on the bell, thereby actuating the same and keeping up the ringing as long as the grounded circuit is intact, for the reason that the making and breaking of the circuit at the central would involve labor and time.

Second. The flow of the current from battery 31 through the electromagnet 25^a will exert on the armature 13^a an influence strong enough so that the later magnetization of the core 11^a will not be able to pull this armature away from its resting-place, and this fact has to be borne in mind so as to understand the later operations. The bell at the station A will ring till the subscriber, through the removing of his receiver, breaks the contact of the lever 3^a with the ground 6^a, when the ringing will cease. The closing of the circuit of the subscriber A will result in, first, the establishing of a circuit including the telephonic device 4^a, line 1^a, battery 9, wire 8^a, coil 7^a, line 2^a, and lever 3^a; but as, as said above, the armature 13^a is tightly held by the energized electromagnet 25^a the circuit including the lamp 16^a will not be made and that lamp will not glow.

Third. The flow of the current of the battery 31, interrupted entirely by the grounds, will now be as follows: battery 31, wire 30, 130

lamp 29, plug 34, tube 48^a, branch wire 27^a, wire 26^a, coil 25^a, coil 10^a, armature 12^a, which armature is now drawn toward the core 11^a and in contact with the wire 23^a, 5 wire 23, armature 12, coil 10, electromagnet 25, wire 26, wire 28, back to the negative pole of the battery. The situation, as far as the armatures of the coils 10 and 10^a is concerned, will therefore be as follows: Of the 10 circuit B the armature 12 will rest against the end of wire 23 and the armature 13 will have been drawn away from wire 21 and will rest in a position where it does not contact with any of these wires. Of the circuit A the 15 armature 12^a will be in electrical contact with wire 23^a and the armature 13^a will be in a position where no contact is made with any of the wires. The conversation between the two subscribers will now be carried on in the 20 following manner: The vibrations set up at the station B will be repeated from coil 7 into coil 10. From there the impulses will flow through armature 12, wire 23, wire 23^a, armature 12^a, coil 10^a, electromagnet 25^a, wire 25^a, branch line 27^a, tube 48^a, plug 34, lamp 29, battery 31, wire 28, wire 26, electromagnet 25, back to its point of starting—that is, 25 back to coil 10. The speech from subscriber A will be transmitted as follows: The vibrations set up at 4^a will flow through the coil 7^a, repeated in the coil 10^a, and will then flow through 12^a, 23^a, 23, 12, 10, 25, 26, 28, battery 31, lamp 29, cord 33, plug 34, tube 48^a, branch circuit 27^a, wire 26^a, electromagnet 30 25^a, back to coil 10^a. When subscriber B is talking, the impulses generated at his station and flowing through its own coil 10 and then through coil 10^a of subscriber A will be repeated in the coil 7^a of said subscriber, and he 35 will therefore be able to listen to same. The impulses generated at the station of subscriber A and flowing through its own coil 10^a and then through coil 10 of subscriber B will be repeated in coil 7, and the subscriber B 40 will be able to listen to the impulses transmitted from A. During all the time the lamp 16 will be extinguished—that is, as soon as the communication of these two subscribers commences; but the lamp 29 will 45 glow during the whole time of such conversation and will be extinguished only when subscriber B replaces his receiver, thereby breaking the circuit with the common battery 22. Thus it will be seen that with the aid of these 50 two lamps 16 and 29 the operator will be notified, first, when the subscriber in her charge is calling, and she will also know after she has made the connections when the communication between the subscriber calling 55 and the subscriber called has ceased. It will be noticed by a perusal of this drawing that this system is minus the supervisory lamp, this for the reason that lamp 29 takes entirely the place of the supervisory lamp of ten- 60 day. As long as this lamp glows the opera-

tor has to leave the respective plug in the jack; but when this lamp is extinguished the operator knows that the circuit is now idle and the plug should be withdrawn. All the operations therefore that the operator has to 70 perform are manipulating her listening-key and placing one single conductor into a metallic tube and withdrawing said conductor at the notification through her annunciator. The workings of this system are positive 75 and the number of devices are reduced to a minimum as compared with the number of devices now in use in exchanges, and, what is more, the operator can have her attention concentrated on her desk, as the devices on her 80 desk will notify her plainly what to do.

I will come now to the construction of the switchboard which is one of the individual features of my invention. It is well known that the jacks and plugs of to-day consist of 85 a rather complicated arrangement whereby parts of the circuit have to be broken or whereby parts have to be made, the plug and jack each consisting of separate contacts and springs. The space such a jack occupies has to be rather a large one, comparatively speaking; but with my improved jack and plug this space can be greatly reduced, and in Fig. 4 the illustration shows a jack 90 and plug of about full size—that is, the space 95 of nearly an inch usually taken up by one jack of to-day can be reduced with the aid of my invention to a space of about three-eighths of an inch, and a switchboard which to-day can accommodate only five thousand 100 subscribers with my arrangement can accommodate ten thousand subscribers or more. Besides, whereas each jack of the switchboard as now employed requires two incoming and two outgoing wires, with my invention only one incoming wire is necessary, a gain which will be readily appreciated by 105 persons versed in the art.

I have not illustrated the arrangement by which a subscriber of one exchange may be 110 connected to a subscriber of a second exchange through one of the lines connecting both exchanges together, as this will form part of another application. It suffices to state here that in connecting one of the subscriber-circuits to a trunk-circuit I also make use of the plug 34, as illustrated, and another conductor, which in Fig. 1 is designated by the number 49, but is, in this figure, broken off, not showing the end terminal, for the reason that the mode of connecting a circuit to a trunk-line, as said above, will form the subject of a different application. It is obvious that battery 31 is not sufficient to effect the armature 12^a when the circuit is closed 115 through the winding 10^a, and this armature is therefore at rest during this operation.

Having now described my invention, what I claim as new, and desire to secure by Letters Patent, is— 120

1. In a telephonic system wherein two or more outlying circuits center in one exchange, a repeater for each of said circuits, one coil thereof connected in said circuit, the 5 second coil thereof connected with a localized circuit, an annunciator in said localized circuit, a source of current for said circuit, said circuit normally open but adapted to be closed through the armature of said repeater, 10 a conducting-line connected with one terminal to said second coil and connected with the other terminal in multiple arc to one jack in each of the switchboards, a second annunciator, a source of current, and connecting- 15 plug in electrical contact with said conducting-line.

2. In telephony, the circuits of two or more outlying stations centering in one exchange, each circuit provided with a repeater, one coil of said repeater connected directly to the outlying circuit, the second coil of said repeater adapted to be connected electrically to said outlying circuit through the armature of said repeater, each of said repeaters provided with means to close a second circuit independent of the cord-circuit, a 20 second circuit, a source of current for said second circuit and an annunciator therefor, each repeater also provided with means to 25 connect thereto one jack in each of the switchboards located in said exchange.

3. In a telephonic exchange a series of repeaters connected each with one coil to an outlying station and connected each with one 35 coil to a series of jacks, each of said jacks located in a separate switchboard, the second of said coils adapted to be connected to the armature of said repeater of said outlying circuit when not in use and adapted to be connected when in use to a second circuit a 40 source of current and an annunciating device for said second circuit.

4. In a telephonic system wherein two or more outlying circuits center in one exchange, 45 means in said exchange for each of said circuits to repeat the impulses transmitted, means to establish a circuit including the repeating means of two circuits, said means consisting of a single conductor normally 50 connected to one of said circuits a plug connected to one of said circuits, both of said circuits adapted to be connected through the insertion of said plug in one of the jacks pertaining to one of said circuits.

5. In combination with a telephonic circuit centering in an exchange, a source of current included in said circuit, an electromagnetic device included in said circuit, said electromagnetic device provided with two 60 armatures, a second source of current, a circuit for said source, and an annunciator for said circuit, the terminals of said circuit adapted to be brought in electrical contact through said armatures, one of said armatures normally in contact with one of the

lines of said circuit, but adapted to break said contact as soon as said electromagnetic device is energized.

6. In combination with a telephonic circuit centering in an exchange, a source of current for said circuit, a repeater for said circuit, said repeater provided with two armatures, a second circuit, and a source of current for said second circuit, said second circuit normally open but adapted to be closed through the energizing of the core of 75 said repeater, an annunciator for said second circuit, adapted to be made active through the closing of said circuit.

7. In combination with a telephonic circuit centering in an exchange, a repeater for said circuit, one coil of said repeater connected in said circuit, the second coil connected to a localized circuit, an annunciator, a source of current for said localized circuit, 85 said localized circuit adapted to be operated through the armature of said repeater, a second annunciating device, a circuit for said device, a source of current for said circuit, a plug connected to said circuit, said annunciating device adapted to be made operative through the insertion of the plug in a second 90 telephonic circuit.

8. In a telephonic system wherein two or more circuits center in one exchange, a repeater for each of said circuits, an annunciator means operatively related to said repeater to make active the annunciator pertaining to said circuit, a source of unidirectional current including a second annunciator 100 connected normally to one coil of said repeater and provided with means to be connected to a second circuit and means whereby the repeated impulses of one circuit are transmitted over a circuit including a coil of 105 a repeater pertaining to a second circuit, and whereby the second annunciator is made active as long as said repeating-circuit is maintained.

9. In combination with a telephone system 110 wherein two or more circuits center in one exchange, connecting means and repeating-coils in said exchange, said connecting means consisting of a single conductor located in the switchboard and normally connected 115 electrically to the repeating-coil of one circuit, and a second conductor, movable, and adapted to be brought into electrical contact with said first conductor, said second conductor connected electrically to the repeating-coil of a second circuit.

10. In combination with two telephonic circuits centering in one exchange, each provided with a repeating-coil, connecting means to connect said two circuits inductively for 125 the purpose of intercommunication, said connecting means consisting of a stationary jack located in the switchboard and a movable plug, said stationary jack consisting of one single conductor connected to a repeat- 130

ing-coil of one of said circuits, and the plug consisting of a single conductor normally connected to a repeating-coil of the second of said circuits designed to be connected to the said first circuit.

5 11. In combination with two or more telephonic circuits centering in one exchange, a repeater for each of said circuits, annunciating means in operative relation to the armature of the repeaters for each of said circuits, a generator of electricity and an electromagnet for the circuit of said annunciating means, and a third circuit including a source of current, said third circuit operatively connected to the grounded armature of said electromagnet.

12. In combination with two telephonic circuits centering in one exchange, repeating means for each of said circuits, a series of 20 switchboards in said exchange, each of said switchboards embracing one terminal of the repeating means of each of said circuits, connecting means for each of said circuits, each of said connecting means normally in 25 electrical connection with the repeating means of one of said circuits, in a manner so that through the electrical connection of the connecting means of one circuit with the

switchboard-terminal of a second circuit, a repeating-circuit is established including 30 the repeating means of both circuits.

13. In combination with two telephonic circuits centering in one exchange, means to connect said two circuits inductively for the purpose of communication, said means 35 embracing a repeater for each of said circuits, one coil of each of said repeaters included in one of said circuits, the second of said coils each connected to a localized circuit and in operative relation to its subscriber-circuit through its own armature, a single conductor connected with one terminal to one of the coils of the repeaters for each of said subscriber-circuits, a series of jacks connected in multiple arc to each of said single 40 conductors and a single-line plug adapted to be inserted in one or the other of said jacks for each of said circuits.

In testimony whereof I hereby sign my name, in the presence of two subscribing witnesses, this 5th day of April, A. D. 1904.

ISIDOR KITSEE.
